UNITED STATES PATENT OFFICE.

WARD S. IRELAND, OF OWENSBORO, KENTUCKY.

STENOGRAPHIC WRITING-MACHINE.

1,098,118.

Specification of Letters Patent. Patented May 26, 1914.

Application filed March 11, 1913. Serial No. 753,635.

To all whom it may concern:

Be it known that I, WARD S. IRELAND, a resident of Owensboro, in the county of Daviess and State of Kentucky, have invented certain new and useful Improvements in Stenographic Writing-Machines; and I do hereby declare the following to be a full, clear, and exact description of the invention, such as will enable others skilled 10 in the art to which it appertains to make and use the same.

This invention relates to improvements in typewriting machines and more particularly to paper feeding mechanism therefor,—the 15 object of the invention being to provide simple and efficient means for insuring sufficient slack in the paper to prevent possibility, under all circumstances, of the paper being torn by the feeding fingers after the type 20 has pressed the paper against the yielding platen.

With this object in view, the invention consists in certain novel features of construction and combinations of parts as hereinafter set forth and pointed out in the 25 claims.

In the accompanying drawings; Figure 1 is a sectional view of a portion of a typewriting machine showing an embodiment of 30 my invention; Fig. 2 is a detail sectional view illustrating the position or condition of the paper strip with relation to the guiding devices at the instant that a type presses the paper strip against the platen; Fig. 3 35 is a perspective view showing the platen and the paper guiding devices associated therewith, and Fig. 4 is a sectional view illustrating a slight modification.

1 represents a portion of the frame of a 40 typewriting machine, wherein is pivotally mounted a plurality of key levers 2 provided respectively with keys or buttons (not shown) and with upwardly projecting arms 4. A notched bar 5 is disposed transversely 45 in the upper portion of the frame work intermediate the ends thereof and in this notched bar, type levers 6 are pivotally supported between their ends and each provided at its upper end with a type 7,—the lower 50 ends of said type levers having loose pivotal connection with the upper ends of the key lever arms 4.

Brackets 8 are located on the frame 1 at respective sides thereof and to the forward

ends of these brackets, links 9 are hinged 55 and supported by the frame work. The forward ends of these links support a transverse platen bar 10, preferably provided with a yielding strip or platen 11.

A shaft 12 (mounted in the brackets 8) 60 extends from one of said brackets 8 to the other and upon this shaft disks, such as indicated at 13, Fig. 1, are mounted. Levers 14 are mounted between their ends on the shaft 12 in proximity to the brackets 8 and 65 the upper ends of these levers carry spring pressed feed fingers 15, which coöperate with certain of the disks 13 to feed the paper and suitable means (not shown) are provided to prevent retrograde movement of 70 the paper after the latter has been fed forwardly.

Standards 16 rise from the platen bar 10 and between these standards, guide rolls 17—18 are mounted. A guide 19 is disposed 75 below the platen bar and may be in the form of an integral flange depending from the lower edge of said bar. A door 20 is provided for the rear end of the casing of the machine and this door carries a bracket 21 80 in which a supply roll of paper 22 is mounted. The paper strip 22 extends from this roll under the guide 19; then upwardly in front of the platen to and over the upper feed roll 17. After passing over the roll 17, the pa- 85 per strip is made to pass downwardly and around the roll 18 and from the latter the strip passes rearwardly over the feed disks 13 and under the feed fingers 15.

A universal bar 23 is supported by links 90 24 pivotally attached at their upper ends to the notched bar 5,—said universal bar being located in front of the upper portions of the key lever arms 4 and preferably provided with a cushion 25 to be engaged by 95 said key lever arms. The links 24 are made in the form of arms rising from bars 26 which project rearwardly from the ends of the universal bar and to the rear ends of said bars 26, links 27 are pivotally attached, 100 the rear ends of said links 27 being pivoted to the lower arms of levers 14. The links 24 have connected thereto springs 28, and the latter are also attached to the frame 1 for returning the parts to and maintaining 105 them in their normal positions.

Suitable inking mechanism is provided, but as the details of construction of this

constitute no part of my present invention, it is unnecessary to make further reference thereto, except to say that the inking ribbon 29 passes between the type on the type levers 5 and the paper strip.

It will be observed that the paper strip is bowed or loose between the guides 17 and 19 and that when a key lever is operated, the type will be caused to imprint on this 10 loose or bowed section of the paper strip. It will also be observed that when a key lever is operated, the engagement of its arm 4 with the universal bar 23 will cause motion to be transmitted, through the arms or bars 15 26 and links 27 to the levers 14. Said levers will thus be caused to rock and to move the feeding fingers 15 and, said feeding fingers being in engagement with the paper strip passing over the disks 13, will cause 20 said paper strip to be moved forwardly a distance sufficient to receive another line of writing and retrograde movement will be prevented by my suitable means as before stated.

25 The connecting devices between the universal bar and the paper feeding devices should be such that the completion of a feeding movement of the paper and the engagement of a type with the paper will be 30 practically simultaneous. As the paper feeding fingers and type bars are both moved simultaneously by the universal bar, the fingers will feed paper as long as a type bar moves. If the type bar moves after 35 gripping the platen, on account of the pliability of the platen face, the fingers will be feeding paper forward after the type has caught the paper and held it; hence there must be some slack in the paper between the 40 type and fingers for the fingers to feed to prevent their catching the paper and tearing it. By arranging the guides for the paper in front of the platen, in the manner above explained, the slack in the paper, 45 which can be taken up by the feeding fingers after the type strike, will be provided and in many instances this will be sufficient.

When a fresh supply roll of paper is 50 placed in the brackets 21, it will be so disposed that the paper strip will feed from the bottom of the roll and in such case the devices hereinbefore described whereby slack is provided, will be sufficient, but it 55 may be desired to write upon the other or rear face of the paper strip, and, when both faces of the strip are thus utilized to receive writing and the roll is placed in the brackets 21 so that the said rear face of the 60 strip may be presented to the writing mechanism, it is necessary to place said roll of paper in the bracket 21 in such manner that the strip will feed from the top of the roll as shown in Fig. 1 of the drawing. It is 5 apparent that when the paper strip is fed

from the top of the roll, the angularity of the strip as it passes the guide 19 will be much sharper than when the strip is fed from the bottom of the supply roll and hence more frictional resistance to the 70 movement of the strip will be caused. Under these conditions, the guide devices above described may not afford sufficient slack in the paper between the type and the platen and it is to insure adequate slack that my 75 present improvements are designed. Thus a weight in the form of a rod or roller 20^a is caused by its own gravity to engage the paper strip between the guide roll 18 and the paper feed devices. This weight or 80 roller is carried at the end of two arms or links which are pivotally attached to the standard 16, preferably coincident with the axis of the guide roller 18. When the feeding mechanism is operated in the manner 85 hereinbefore described, the paper strip between the guide roller 18 and the feed devices will become taut and raise the weight or roller 20^a and as soon as the type move in a direction away from the platen and thus 90 releases the paper strip, said weight or roller will descend upon the paper strip and act to pull a short portion thereof over the guides 17 and 18 and thus compensate for any frictional resistance to which the 95 paper strip may have been subjected on account of the sharp angle at the guide 19 and insure sufficient slack in the paper passing in front of the platen to accomplish the results in the feeding of the paper as here- 100 inbefore explained.

When the weight or roller 20^a is used, the upper guide roller 17 may be dispensed with and the paper caused to pass directly from the guide roller 18 under the weight 105 or roller 20^a as illustrated in Fig. 4.

Having fully described my invention, what I claim as new and desire to secure by Letters Patent is;

1. In a typewriting machine, the combination with framework, a platen mounted therein, paper guiding means spaced from the platen, paper feeding means rearwardly of the platen, and operating means for the paper feeding means, of a yielding tension roller supported by the framework independently of the feeding means and the operating means for the latter, said tension roller being located to engage the paper at a point between the guiding means and the paper feeding means. 110

115 2. In a typewriting machine, the combination with a platen, type-bars, paper feeding devices, guiding devices for paper passing between the type on the type-bars and the platen, and means for operating the type-bars and feeding devices, of a yielding weight in position to engage the paper between the guiding and feeding devices and operating to depress the paper to produce 120 125 130

slack in that portion thereof passing between the type and the platen, when the type move away from the paper and platen.

3. In a typewriting machine, the combination with a platen, type-bars, paper feeding devices, guiding devices for the paper passing between the type on the type-bars and the platen, and means for operating the type-bars and feeding devices, of pivoted arms and a weight supported by the free ends of said pivoted arms, in position to engage the paper passing between
- 10

the guiding and the feeding devices and operating to depress the paper and produce slack in that portion thereof passing between the type and the platen, when the type move away from the paper and platen. 15

In testimony whereof, I have signed this specification in the presence of two subscribing witnesses.

WARD S. IRELAND.
